UNITED STATES PATENT OFFICE.

BENJAMIN S. FOSS, OF BOSTON, MASSACHUSETTS, ASSIGNOR TO B. F. STURTEVANT COMPANY, OF BOSTON, MASSACHUSETTS, A CORPORATION OF MASSACHUSETTS.

CENTRIFUGAL FAN-WHEEL.

1,038,110.

Specification of Letters Patent. Patented Sept. 10, 1912.

Application filed January 28, 1911. Serial No. 605,235.

To all whom it may concern:

Be it known that I, BENJAMIN S. Foss, a citizen of the United States, residing at Boston, in the county of Suffolk and State 5 of Massachusetts, have invented certain new and useful Improvements in Centrifugal Fan-Wheels; and I do hereby declare the following to be a full, clear, and exact description of the invention, such as will 10 enable others skilled in the art to which it appertains to make and use the same.

The invention relates to that type of centrifugal fans in which the fan wheel is provided with a multiplicity of long narrow 15 blades arranged in drum form.

It is the object of the invention to improve and simplify the construction of small fan wheels of this type so that wheels having the requisite strength and rigidity 20 may be conveniently and economically manufactured. To this end the invention contemplates forming the blading and the end rings for supporting the blades by slitting a sheet metal blank transversely 25 and longitudinally bending only the metal between the slits to form parallel blades, and then bending the blank into cylindrical form and uniting its ends. By thus forming the wheel cylindrical end strips are 30 provided integrally united with the blades which will effectively support the blades when the wheel is run at high speed. It is preferred to so arrange the slits leading longitudinally from the ends of the trans- 35 verse slits that the blades may be bent out of the plane of the end strips without twisting the metal connecting the blades and strips, since a strong and more rigid construction is thereby secured. This may be 40 accomplished by staggering the longitudinal slits and extending them so that the end of each slit is substantially in line transversely of the blank with the end of the succeeding slit, but separated therefrom 45 by intervening metal which is given a straight transverse bend to bring the blade bounded by adjacent transverse slits into the desired angular relation to the end strips. While it is preferred to slit and 50 bend a flat metal strip or sheet to form the blades and end strips, and thereafter bend the blank into cylindrical form, it will be understood that a cylindrical blank may be slit and bent to form parallel blades integrally connected with cylindrical end 55

strips, without departing from the broader features of the invention.

The invention consists in the features of construction and combination of parts hereinafter described and referred to in the 60 claims, the advantages of which will be apparent to those skilled in the art from the following detailed description.

The features of the invention will be readily understood from an inspection of 65 the accompanying drawings, in which—

Figure 1 is a front end elevation of a fan wheel embodying the invention in its preferred form; Fig. 2 is a sectional view on line 2—2, Fig. 1; Fig. 3 is a plan view of a 70 sheet metal blank slit and partially bent to form the construction of blades indicated in Figs. 1 and 2; Fig. 4 is an end view of the blank shown in Fig. 3; Fig. 5 is a sectional view on line 5—5, Fig. 3; Fig. 6 is a 75 plan view showing the shape of the blank after the bending and shaping of the blades has been completed; and Fig. 7 is a sectional view on line 7—7, Fig. 6.

In the construction of fan shown in the 80 drawings the blading and supporting end strips are formed from a sheet or strip of sheet metal having a width corresponding to the length of the fan wheel to be made, and having a length slightly in excess of 85 the circumference of the finished wheel. In forming the blades having the construction and arrangement illustrated in Fig. 1, the blank 1 is subjected to the action of dies which form the transverse slits 2 and the 90 longitudinal or circumferential slits 3 leading from the ends of the transverse slits within the edges of the blank. In the arrangement of blading shown in Fig. 1, the blades 4 lie wholly within the end rings or 95 strips 5 and 6 so that the spaces between the blades are open at the entrance end of the blades. This arrangement of blades is provided for in slitting the blank 1 by arranging the longitudinal slits 3 so that 100 they extend from the ends of the transverse slits 2 into substantial alinement with the succeeding transverse slit. The slits 3 are arranged at an angle or staggered so that 105 the slits do not intersect but leave connecting metal at 7 between the ends of succeeding slits. The dies which slit the blank 1 may be so shaped that they also bend the metal between adjacent transverse slits 2 out of the plane of the marginal strips 5 110

and 6, as indicated in Fig. 5. Since the ends of the slits 3 are substantially in line transversely of the blank, the metal between the transverse slits 2 may be bent out 5 of the plane of the end strips by a direct transverse bend across the metal at 7. After the blank has been slit and partially bent, as indicated in Fig. 5, it is subjected to the action of another set of dies which 10 give the blades the desired shape and angular arrangement with relation to the end strips 5 and 6. In the construction shown the blades are concaved and are provided with transverse corrugations, as indicated 15 in Figs. 6 and 7. After the blading has been thus bent and shaped, the blank is bent into cylindrical form, and the ends of the blank overlapped and soldered or otherwise secured, as indicated at 8 in Fig. 1. 20 The drum thus formed may be secured to a supporting disk 9 which is provided with a flange 10 fitting within the end strip 6, and with a hub 11 for securing the wheel to a shaft.

25 In bending and shaping the blades only the metal between the transverse and longitudinal slits is bent and shaped, so that when the blank is bent into the form of a cylinder the end strips 5 and 6 form continuous cylindrical supporting rings or strips which will effectively resist the strains developed by centrifugal force when the wheel is driven at a high rate of speed. By extending the longitudinal slits so that the 30 front end of each slit is in line transversely with the rear end of the next succeeding slit a straight transverse bend may be given to the metal between the ends of the slits in bringing the blades into proper angular 35 relation to the end strips so that twisting and distortion of the metal tending to weaken or disrupt it is avoided. By arranging the longitudinal slits in the manner shown in Fig. 3, so that they extend from 40 the end of a transverse slit into transverse alignment with the end of the next succeeding slit, the transverse bend in the metal between the blade and end strip may be 45 made substantially in line with the outer edge of the blade, so that the outer edge of the blade is in the plane of the end strips. This provides a larger inlet opening for the 50 air entering the fan since the entrance end of the blades is open. The ends of the longitudinal slits may overlap somewhat if 55 desired, and the transverse bend in the metal connecting the blades with the end strip may be made so that the outer edges of the blades are somewhat within the 60 periphery of the end strips if desired, but it is preferred to so make the bends that the

outer edges of the blades are substantially flush with the periphery of the end strips as shown.

While it is preferred to employ the arrangement of longitudinal slits shown and described, and to so arrange the slits that the bend in the metal connecting the blades with the end strips is a substantially transverse bend, for the reasons given this arrangement is not essential to the broader features of the invention, and may be varied and modified as found desirable. It will also be understood that the arrangement of the slits and bends, so that the 75 blades lie within the plane of the end strips, is not essential to the broader features of the invention, and that the arrangement of the slits and bends may be varied as found most desirable or best suited to the conditions under which the wheel is to be used.

Having explained the nature and object of the invention, and specifically described one form of wheel in which it may be embodied, what I claim is:—

1. A centrifugal fan wheel comprising a cylindrical metal sheet having a series of parallel transverse slits and non-intersecting slits extending longitudinally from the ends of the transverse slits within the edges 90 of the sheet to leave cylindrical marginal strips along the edges of the sheet, and having only the metal bounded by the transverse and longitudinal slits bent at an angle to the end strips to form parallel blades 95 integrally connected with the continuous cylindrical strips, substantially as described.

2. A centrifugal fan wheel comprising a cylindrical metal sheet having a series of transversely parallel slits and slits extending longitudinally from the ends of the transverse slits with their ends in transverse alignment and separated by intervening metal which is bent transversely to bring the blades bounded by the slits into 105 uniform angular relation to the strips between the edges of the sheet and the longitudinal slits, substantially as described.

3. A centrifugal fan wheel comprising a sheet metal strip bent into cylindrical form 110 and having transverse slits 2 and longitudinal slits 3 extending from the ends of the slits 2 into transverse alignment to the succeeding slit 2 and separated therefrom by intervening metal 7 which is bent to bring 115 the blades 4 bounded by the slits 2 and 3 into uniform angular relation to the end strips 5 and 6, substantially as described.
